GLASSES CASE HOLDER

Elaine J. Ackerman and Michael J. Ackerman,
Atlanta, Ga.

Application March 12, 1949, Serial No. 1,372

Term of patent 7 years

(Cl. D57—1)

To all whom it may concern:

Be it known that we, Elaine J. Ackerman and Michael J. Ackerman, both citizens of the United States, both residing at Atlanta, in the county of Fulton and State of Georgia, have invented a new, original, and ornamental Design for a Glasses Case Holder, of which the following is a specification, reference being had to the accompanying drawing, forming part thereof, and wherein:

Fig. 1 is a front elevational view of a glasses case holder, showing our new design;

Fig. 2 is a right side view thereof; and

Fig. 3 is a rear elevational view of the disclosure in Fig. 1.

We claim:

The ornamental design for a glasses case holder, substantially as shown.

ELAINE J. ACKERMAN.
MICHAEL J. ACKERMAN.
